UNITED STATES PATENT OFFICE.

DAVID L. WINTERS, OF PHILADELPHIA, PENNSYLVANIA.

DECARBONIZER FOR GAS-ENGINES.

1,261,467.

Specification of Letters Patent. Patented Apr. 2, 1918.

Application filed August 9, 1917. Serial No. 166,268.

To all whom it may concern:

Be it known that I, DAVID L. WINTERS, a citizen of the United States, residing at Philadelphia, in the county of Philadelphia and State of Pennsylvania, have invented 5 certain new and useful Improvements in Decarbonizers for Gas-Engines, of which the following is a specification.

This invention relates to decarbonizers for 10 gas engines and more particularly to a valveless attachment associated with the intake manifold adapted to reduce carbonization of the cylinders, spark plugs, etc.

One of the objects of the present invention 15 is to provide a simple and practical device of the above general character having relatively few parts which will be inexpensive to manufacture and install. A further object is to provide a device of the above character 20 permitting ready adjustment yet to be free from valves. A further object is to provide a device of the above general character for admitting a certain amount of moisture to the explosive charge whereby a 25 greater expansion thereof will take place resulting in a more economical and smoother operation of the engine. A further object is to prevent carbonizing of the spark plugs and an accumulation of carbon within the 30 cylinders.

Other objects will be in part obvious from the annexed drawings and in part indicated in connection therewith by the following analysis of this invention.

This invention accordingly consists in the 35 features of construction, combination of parts and in the unique relations of the members and in the relative proportioning and disposition thereof; all as more completely outlined herein.

To enable others skilled in the art so fully to comprehend the underlying features thereof that they may embody the same by the numerous modifications in structure and 45 relation contemplated by this invention, drawings depicting a preferred form have been annexed as a part of this disclosure, and in such drawings, like characters of ref-

erence denote corresponding parts throughout all the views, of which:

Figure 1 is an elevational view showing the attachment applied to the engine of an automobile, certain parts being shown in section or broken away in order that the invention may be fully understood.

Fig. 2 is an enlarged detail view.

Referring now to the drawings in detail and more particularly to Fig. 1, 5 denotes the radiator of an automobile in its usual position in front of the engine. A carburetor 6 is adapted to supply the explosive mixture to the engine through an intake manifold 7. A throttle valve 8 is positioned in this manifold and preferably adjacent the throttle valve or other convenient place in the intake manifold there is inserted an annular gasket 10 of lead or other suitable semi-compressible material through which diametrically passes a tube 11, the opposite end 12 of which dips down into a tank 13 provided with an inlet or filling opening 14. If desired, this tank may be supplied or filled from the overflow of the radiator 5 by means of a connecting pipe 15. This is not always satisfactory as a certain amount of sediment and rust might pass through the pipe 11 to clog the subsequent parts of the attachment as will appear hereinafter. If, however, this is done, a filter device 16 is preferably provided for the purpose of taking up as much sediment as possible prior to the admission of water to the tank 13.

The pipe 11 is preferably of copper tubing about one-eighth of an inch in diameter and that portion passing through the gasket 10 is provided with a small opening 17 about one-sixty-fourth of an inch in diameter facing toward the engine.

It will be noted also that the pipe 11 projects entirely through the gasket and its open end is closed by an air filter and regulator 18. This air filter is preferably formed of a wire wound or covered with filtering material. In fact, an ordinary pipe stem cleaner is found to work very satisfactorily. Likewise the opposite end 12 of the pipe 11

is provided with a similar adjustable filter device 20 for filtering the water prior to its passage into the pipe 11 and regulating the amount of flow. The level of the water is 5 preferably kept at such height as to prevent siphoning.

By moving the air filter and the water filters relatively to the ends of the pipe the amount of air and the amount of water may 10 be regulated and proportioned, as desired.

The ends of the wire are bent over to hold them in adjusted position. In other words, the construction constitutes a valveless water carbureter in which both the air inlet and 15 the water inlet are controlled by a mechanism which performs the dual function of regulating proportionately the volume of air and water admitted and at the same time acting to filter both the air and water so 20 admitted, to prevent clogging of the outlet.

It is therefore believed that the present invention comprises a simple and practical attachment particularly adapted for use in connection with the carbureter of gas engines for the purpose of accomplishing, 25 among others, all the objects and advantages set forth, such as preventing carbonization of the cylinders and spark plugs, and for producing a more economical and smoother 30 operation of the engine.

Without further analysis, the foregoing will so fully reveal the gist of this invention that others can by applying current knowledge readily adapt it for various applications without omitting certain features 35 that, from the standpoint of the prior art, fairly constitute essential characteristics of the generic or specific aspects of this invention, and therefore such adaptations should 40 and are intended to be comprehended within the meaning and range of equivalency of the followings claims.

I claim:

1. In a device of the character described, 45 the combination with an intake manifold, of a water supply, a pipe adapted to take water from said supply at a point below the plane of said manifold and open to the atmosphere at its opposite end, the said pipe 50 being provided intermediate its ends with a relatively minute feed opening into said manifold, whereby water is fed to the manifold in regulated quantity proportioned to the air supplied thereto.

55 2. In a device of the character described, the combination with an intake manifold, of a water supply, a pipe adapted to take water from said supply at a point below the plane of said manifold and open to the atmosphere at its opposite end, the said pipe 60 being provided intermediate its ends with a relatively minute feed opening into said manifold, whereby water is fed to the manifold in regulated quantity proportioned to

the air supplied thereto, and a water and 65 air proportioning and detritus excluding medium within said pipe.

3. In a device of the character described, the combination with an intake manifold, of a water supply, a pipe adapted to take 70 water from said supply at a point below the plane of said manifold and open to the atmosphere at its opposite end, the said pipe being provided intermediate its ends with a relatively minute feed opening into said 75 manifold, whereby water is fed to the manifold in regulated quantity proportioned to the air supplied thereto, and a water and air proportioning and detritus excluding medium within said pipe and extending be- 80 yond the ends thereof.

4. In a device of the character described, in combination with an intake manifold, a source of water supply, a pipe connecting said water supply with the interior of the 85 manifold and having a small outlet hole therein, the ends of said pipe being open and longitudinally adjustable filtering means positioned in said ends for regulating the amount of water and air admitted there- 90 through and simultaneously filtering the same.

5. In a device of the character described, in combination with an internal combustion engine, and an intake manifold, a water supply, a pipe leading from said water supply to the intake manifold having a small opening to the manifold, and adjustable means in the ends of said pipe adapted to regulate the amount of water and air drawn in 100 through said open ends.

6. In a device of the character described, in combination with an internal combustion engine and an intake manifold, a water supply, a pipe with open ends leading from 105 said water supply to the intake manifold having a small opening to the manifold and adjustable means in the open ends of said pipe adapted to regulate the amount of water and air drawn in through said open 110 ends, said means comprising a wire covered with filtering material extending into the pipe, the ends of which project outwardly therefrom whereby the same may be conveniently moved in and out.

7. An attachment for gas engines adapted to be placed in the intake manifold comprising a gasket, a pipe having open ends passing through said gasket, and having an outlet hole within the same, and regulating 120 means at the ends of said pipe.

8. An attachment for gas engines adapted to be placed in the intake manifold comprising an annular gasket, a pipe having open ends associated with said attaching member, an outlet hole intermediate the ends and within the gasket, and regulating and filtering means associated with the ends of 125

said pipe whereby the amount and proportion of fluids passing therethrough to the outlet may be controlled.

9. An attachment for gas engines adapted to be placed in the intake manifold comprising a gasket, a pipe associated with said gasket, an outlet hole within the gasket and filtering means associated with said pipe

whereby the amount of fluid passing therethrough to the outlet may be controlled. 10

In testimony whereof I affix my signature in presence of two witnesses.

DAVID L. WINTERS.
